(57) **CLAIM**

The ornamental design for an ottoman, as shown and described.

DESCRIPTION

FIG. 1 is a top, left, rear perspective view of an ottoman showing our new design in an open configuration;

FIG. 2 is a top, right, rear perspective view thereof;

FIG. 3 is a top, right, front perspective view thereof;

FIG. 4 is a top, left, front perspective view thereof;

FIG. 5 is a bottom, right, rear perspective view thereof;

FIG. 6 is a bottom, left, rear perspective view thereof;

FIG. 7 is a bottom, left, front perspective view thereof;

FIG. 8 is a bottom, right, front perspective view thereof;

FIG. 9 is front elevation view thereof;

FIG. 10 is a rear elevation view thereof;

FIG. 11 is a right side elevation view thereof;

FIG. 12 is a left side elevation view thereof;

FIG. 13 is a top plan view thereof;

FIG. 14 is a bottom plan view thereof;

FIG. 15 is a top, left, rear perspective view of an ottoman showing our new design in a transition configuration between the open configuration and a closed configuration; and,

FIG. 16 is a top, right, rear perspective view of an ottoman showing our new design in the closed configuration.

The broken line showing is for the purpose of illustrating portions of the ottoman and forms no part of the claimed design.

1 Claim, 16 Drawing Sheets
